EDWARD A. COLBY, OF MAPLEWOOD, NEW JERSEY, ASSIGNOR TO BAKER & COMPANY, INC., A CORPORATION OF NEW JERSEY

ELECTRIC ANNEALING APPARATUS

Application filed October 21, 1930. Serial No. 490,202.

This invention relates to an apparatus for annealing metals and their alloys in wire or strip form, and is especially applicable to metal wires or strips having a relatively small cross-section or low tensile strength. One important feature of the invention is an improved electric furnace.

It has been common practice for many years to anneal metal wires by coiling them on metal spools as supports in muffle heated furnaces. Unless the wire has an oxide or other protective coating, contacting convolutions of the wire frequently weld together at the annealing temperatures, thereby causing loss of labor and material. The application and removal of any protective coating complicates the process of wire drawing, makes it difficult to secure uniform results, and is not permissible when the wire must be annealed at the finished size. The trend today appears to be toward a revival and improvement of former experimental methods of annealing by the linear passage of wire through refractory tubes heated by coal or gas fuel, or more recently by electric current. Such furnaces are usually arranged with their tubular channels in a horizontal or slightly inclined position, and the wires are drawn through the tubes in contact with the inner walls of the tubes so that the hot wires often become contaminated from the tubes or foreign matter therein, or if sufficient tension is applied to avoid physical contact of the wires with the tubes, the cross-sectional areas of the wires are reduced by the tension.

One object of the invention is to provide a novel and improved annealing apparatus wherein the wire shall be linearly passed through a heated tube in such a manner as to avoid contact of the wire with the walls of the tube and obviate such tensile strain of the wire as would reduce the cross-sectional area thereof.

Another object is to provide an electric annealing furnace for the purpose described including a metal tube through which the wire to be annealed may be passed linearly, said tube itself serving as the resistor to heat the wire passing therethrough and being mounted so as to prevent buckling, bending

or other deformation of the tube as the result of expansion and contraction thereof.

Other objects of the invention are to provide an annealing apparatus of the character described whereby uniformity of annealing of long lengths of wire may be obtained by variable control of both temperature and the period of treatment of wire thereto; to provide such an apparatus whereby the wire may be successively annealed and drawn; to provide an electric annealing furnace embodying novel and improved features of construction whereby economy of heat transferred from the furnace to the wire being annealed is attained and external radiation reduced to a minimum; to obtain any desired speed of heating or of cooling of the furnace and the material being annealed to facilitate manual handling of the furnace or the material, and to obtain other advantages and results as will be brought out by the following description.

For the purpose of illustrating the principles of the invention I have shown in the accompanying drawings one form of annealing apparatus embodying my invention, but it should be understood that this is primarily for the purpose of illustrating the principles of the invention and that many modifications and changes can be made in the details of construction of the apparatus without departing from the spirit or scope of the invention.

Referring to said drawings, in which corresponding and like parts are designated throughout the several views by the same reference characters,

Figure 1 is a front elevation of the annealing apparatus;

Figure 2 is a side elevation thereof;

Figure 3 is an enlarged fragmentary transverse vertical sectional view through the electric furnace embodying the invention, taken on the line 3-3 of Figure 1;

Figure 4 is a similar view showing the apparatus from a position at right angles to that illustrated in Figure 3;

Figure 9 is a similar view showing another attachment for preventing oxidation of the wire during the annealing operation;

Figure 10 is a horizontal sectional view, on the line 10—10 of Figure 1;

Figure 11 is a fragmentary top plan view 15 of the apparatus shown in Figure 1, and

Figure 12 is a fragmentary front elevation of the apparatus showing the manner of using it in connection with a wire-drawing machine.

20 Specifically describing the invention, the apparatus preferably includes a portable stand or support which can be conveniently moved from place to place wherever it is desired to anneal wire or the like, and said stand may consist of a base 1 mounted on casters or the like 2 and having secured thereto four uprights or standards 3 at the top of which is mounted a top piece 4.

Upon this stand is mounted substantially 30 centrally between the standards 3, my improved electric furnace A. This furnace is connected in the secondary circuit of a known type of transformer B and an ammeter C, as by wires 5, 6 and 7. The circuit through 35 the primary winding of the transformer B is controlled by a rheostat D, the current to which from line wires E is controlled by a cut-off switch F. As schematically shown in Figure 2 of the drawings, the secondary 40 of the transformer is connected to one terminal of the ammeter by a wire 8. The transformer B, rheostat D, switch F and ammeter C are mounted upon the stand in any suitable manner, as shown. The constructions 45 of these electrical devices and the circuit connections therefor are all old and well known, and no claim to novelty is made thereon.

The wire or the like to be annealed is wound 50 upon a spool G which is placed upon the base 1 of the stand centrally between the standards and substantially coaxially with the electric furnace A, and the wire H passes vertically upward through the furnace, where the wire is heated for annealing, and 55 then outwardly over a guide pulley I adjustably mounted at K on the stand, from where the wire may be wound upon a drum or reel L actuated by suitable driving mechanism M from a motor or the like enclosed 60 in a casing N. The wire is unwound from the spool and drawn through the furnace by the winding drum L.

However, it is not necessary to use the winding apparatus described, and the wire may 65 be passed directly from the furnace to a

wire-drawing machine, or other machine by which it may be desired to treat the wire subsequently to the annealing operation, as hereinafter described, and accordingly the winding apparatus L, M, N is preferably 70 detachably mounted upon the stand as by brackets O.

Coming now to the electric furnace A, which is the important feature of my invention, the furnace includes an outer wall or 75 casing 9, which is preferably cylindrical and tubular, formed of any suitable material which is a poor conductor of both heat and electricity and has sufficient mechanical strength to serve as a support. One refractory material possessing these desired characteristics is unbaked soapstone, which has the additional advantageous characteristic of being easily machined and susceptible of being made in short sections which can be 80 mechanically connected to provide a furnace wall of any desired length. This insulating casing 9 of the furnace may be supported upon the stand in any suitable manner, as by a bracket arm 10 secured to the casing and 85 adjustably mounted as by a set screw 11 upon one of the standards 3.

Centrally or coaxially within the casing 9 is mounted a tube 12 which serves as the channel through which the wire or the like 90 to be annealed is passed. This tube also serves as the resistor for heating the wire, and is preferably formed of a seamless drawn metal tube of such length, bore, thickness of wall, and other characteristics as may be necessary 95 to satisfy requirements. If the annealing temperatures are to be not above 1,000° C., a nichrome tube may be used, while for higher temperatures up to 1,500° C., alloys of the 100 platinum group of metals are preferable because they are non-oxidizing. For still higher temperatures molybdenum and tantalum can be used if provision is made to keep them bathed in an inert gas.

This resistor 12 is fixedly connected at one 110 end to the upper end of the casing 9, as by a metal cap 13 which has arms to embrace the casing and clamped together by a screw 14, whereby the cap is securely mounted on the casing. The tube preferably has a bushing 15 welded thereto, which is in turn welded to the cap 13. Welded upon the other end of the tube is an exteriorly threaded bushing 16 which passes through an opening in a stirrup-like member 17 and has a nut 18 for 115 clamping said stirrup to the bushing. This stirrup is shown as including four spring arms 19 which radiate outwardly and upwardly and are connected to a split collar 20 secured on the casing in a groove 21 by 120 screws 22. The bushing 16 passes loosely through an opening 23 in a refractory cylindrical block 24 loosely slidable in the casing 9 and supported upon the stirrup 17. With 125 this construction, the tube 12 is suspended so 130

that its weight normally tends to keep it straight, and the lower end is free to move relatively to the casing 9 to compensate for expansion and contraction of the tube as it is heated and cooled, respectively, so that buckling or bending of the tube is prevented.

The block 24 serves to maintain the tube centrally of the casing. The spring arms 19 of the stirrup also normally exert a slight tension upon the tube to aid in preventing bending or buckling thereof. The cap 13 and the collar 20 serve as terminals for connecting the tube in an electric circuit with the transformer B, and preferably a flexible loop 25 formed of a good electrical conducting metal, such as silver, is provided for connecting the two halves of the collar 20 to ensure equal diversion of current between the four spring circuit members 19.

The bore of the tube 12 is made as small as possible for efficiency of operation, and I have found that a one-eighth inch bore is ample for fishing wire through the tube for annealing. It will be noted that the heat is directly transmitted from the resistor tube 12 to the wire being annealed, so that great efficiency in heating is obtained, and the air space between the tube and the casing 9 reduces to a minimum the loss of heat from the resistor externally. Any increase in the diameter of the bore above that needed for the mechanical handling of the wire to be annealed, results in a loss of efficiency in the transmission of heat to the work, both because of greater space between the wire and the tube and the greater radiating surface of the tube, and any contact of said tube with heat conducting material would result in a loss of heat from the tube.

In operation of the apparatus, the wire to be annealed is drawn from the spool or drum G through a guiding eye 26 disposed below and in axial alignment with the lower end of the resistor tube 12, after which the wire is threaded through the resistor tube upwardly and over the pulley I at the top of the stand. From this pulley the wire may be directly connected to a wind-up drum L, or if desired, passed directly through wire-reducing dies P, as shown in Figure 12 of the drawing. When it is desired to draw the wire immediately after annealing, the stand may be moved alongside of and connected to a wire-drawing machine Q by a suitable bolt and nut connection R. The wire is then drawn through the resistor tube and is suspended from the pulley I so as to remain substantially centrally of the resistor tube and out of contact therewith. The only tension on the section of the wire is caused by the weight of the wire, so that there is a minimum tendency toward reduction in cross-sectional area of the wire while it is being annealed. Upon turning on the switch F, the desired temperature of the tube 12 may be obtained almost

instantaneously by adjustment of the rheostat D, as there is no solid body conduction of heat from the resistor except at its terminals. This construction effects not only high efficiency in heat transfer from the tube 12 to the wire, but, upon opening of the switch F, equally rapid cooling of the tube results so that the fishing of new wire through the tube and handling of the furnace is greatly facilitated.

Variations of annealing temperatures may be controlled according to the rate of heat development in the resistor tube which is indicated by the ammeter C, current flow, or by a thermo-couple in contact with the external wall of the tube 12, while the time of annealing may be controlled both by the length of the resistor tube 12 and the speed of movement of the wire therethrough. Absorption of heat by wire passing through the resistor tube is practically instantaneous, so that for ordinary speeds of wire drawing, wires of .025 inches are thoroughly annealed by passage through a resistor tube of one-eighth inch bore and a length of thirteen inches when the temperature of the metal of the resistor tube is approximately 1,500° C.

When it is desired to anneal oxidizable metals in this type of furnace, detachable extensions may be added to both ends of the resistor tube. For example, when it is desired to gradually reduce the temperature of the wire after it emerges from the resistor tube, so as to prevent oxidation of the wire, an extension 27 is attached to the cap 13, as shown in Figure 8 of the drawings. This extension may consist of a hollow casing having centrally thereof a tube 28 to be aligned with the resistor tube 12. In the space 270 between the tube 28 and the walls of the casing may be circulated a cooling liquid, such as water, through pipe connections 29 and 30. Such a construction ensures the cooling of the annealed wire below its oxidation point on its emergence to the outer atmosphere.

Oxidation of the wire passing through the furnace may also be prevented by detachably connecting a block 31 to the nut 18 at the lower end of the resistor tube, as shown in Figure 9; said block having a central passage 32 to align with the resistor tube 12 and through which passes the wire, and a lateral passage 33 communicating with the passage 32 and to be connected as by a pipe 34 to a supply of steam or dry inert gas. Upon injection of steam or an inert gas into the passage 32, the steam or gas passes downwardly and outwardly through the passage 32 in a direction opposite to that of the travel of the wire, and some of the gas passes upwardly and outwardly through the resistor tube, so that the wire being annealed is bathed in the steam or gas, and oxidation of the wire thereby prevented.

It will be understood that while I have

shown and described the apparatus for annealing a single wire, the diameter of the resistor tube 12 can be enlarged to permit the simultaneous passage of several wires there-through properly guided at both the lower and upper ends. However, it is practical and economical to use separate resistor tubes for each wire being annealed. To increase the output of the apparatus, both the length 10 of the resistor tube and the speed of travel of the wire therethrough may be increased.

While I have shown and described the invention as embodied in certain details of construction, it should be understood that this is 15 primarily for the purpose of illustrating the principles of the invention, and that many modifications and changes may be made in the details of construction, by those skilled in the art, without departing from the spirit 20 or scope of the invention.

Having thus described the invention, what I claim is:

1. An apparatus for annealing long continuous pieces of material, comprising a heat 25 insulating casing, a tube of electricity-conducting material suspended in insulated relation at its upper end substantially vertically in said casing and in spaced relation between its ends to the inner walls of said casing so as 30 to provide a heat insulating air space between the casing and said tube with the lower end of said tube free for movement upon expansion and contraction of the tube, through 35 which the material to be annealed is linearly passed, so that gravitational action tends to prevent buckling or bending of said tube and the tube is relieved of all friction resistance to expansion and contraction, and means for 40 connecting the opposite ends of said tube in an electric circuit.

2. An apparatus for annealing long continuous pieces of material, comprising a heat insulating casing of tubular form, a tube of electricity conducting material suspended in 45 insulated relation at its upper end substantially vertically in said casing and in spaced relation between its ends to the inner walls of said casing with its lower end free for movement upon expansion and contraction of the 50 tube, through which the material to be annealed is linearly passed, means substantially closing said casing interposed between the lower end of said tube and said casing for holding the tube in spaced relation to the inner walls of said casing, whereby a heat insulating air space is provided between said 55 tube and said casing and a minimum of heat conducting contact of said tube with other parts is ensured, and gravitational action tends to prevent buckling or bending of said 60 tube and the tube is relieved of all frictional resistance to expansion and contraction, and means for connecting the opposite ends of said tube in an electric circuit.

3. An apparatus for annealing long con-

tinuous pieces of material, comprising a support, a tube of electricity-conducting material suspended only at its upper end in insulated relation substantially vertically on said support and free throughout its length 70 for movement upon expansion and contraction of the tube, through which tube the material to be annealed is linearly passed, means for connecting the opposite ends of said tube in an electric circuit, and a spring connection between said support and the lower end of said tube to exert slight tension on the tube to restrain buckling or bending thereof. 75

4. An apparatus for annealing long continuous pieces of material, comprising a heat 80 insulating casing of tubular form, a metal cap at the upper end of said casing, a tube of electricity-conducting material suspended at its upper end on said cap substantially centrally and vertically in said 85 casing and in spaced relation to the walls thereof with its lower end free for movement upon expansion and contraction of the tube, through which tube the material to be annealed is linearly passed, means at the lower 90 end of said tube for holding it centrally of said casing, means for connecting said cap in an electric circuit, and a spring connection between said casing and the lower end of said tube to exert slight tension on the tube to restrain buckling or bending thereof and for connecting said tube in an electric circuit. 95
